TELEPHONE SYSTEM

Oliver Irving Carpenter and Benjamin Francis Moss, Coventry, England, assignors to The General Electric Company Limited, Coventry, England

Application December 2, 1935, Serial No. 52,532
In Great Britain December 19, 1934

7 Claims. (Cl. 179—27)

The present invention relates to telephone systems and is more particularly concerned with arrangements for detecting faults occurring in automatic or semi-automatic exchanges. It has 5 for its object the provision of means whereby an operator at an attended exchange is informed of the occurrence of a fault at an unattended exchange connected to the one at which the operator is situated.

10 In such unattended exchanges, a line fault has hitherto been caused, after the lapse of a predetermined period, to lock the affected line out of use, and release any common exchange apparatus which has been held operated by the fault. 15 This, in the case of an exchange difficult of access, may mean that the particular subscriber's line on which the fault occurs is liable to be out of commission for several days.

According to the invention therefore, means 20 are provided in an unattended automatic exchange connected to an attended exchange, whereby on the occurrence of a line or like fault at the former exchange, an operator at the latter exchange is informed, and may ascertain the number of the faulty line. The operator may 25 also connect to the said faulty line, and apply a tone such as a howler.

In an embodiment of the invention an unattended rural automatic exchange is connected by 30 one or more junctions to an attended or parent exchange. If a line fault at the rural exchange occurs, the faulty line is isolated from the common exchange apparatus after a predetermined period, the said exchange apparatus being released. In addition, the faulty line seizes a group 35 of common apparatus connected via a junction to the parent exchange, and the said common apparatus causes a signal to be sent over the junction which informs the operator at the parent exchange that attention is required.

40 The operator connects her telephone circuit to the junction and receives a characteristic tone. She now dials a series of 1's until the characteristic tone is removed. The total of 1's dialled, is 45 now the first figure of the number of the faulty line. After a short time, the tone is replaced on the line, and the operator dials a further train of 1's counting during the process. Removal of the tone a second time gives the second figure 50 of the faulty line's number. The process is repeated as many times as there are digits in this number.

When the operator has ascertained the number 55 of the faulty line, she may attempt to speak to the subscriber connected to it, or may connect

a tone to the said line such as a howler. Disconnection of the operator's circuit from the junction leaves the faulty line locked out in such a manner that it cannot again seize the junction and warn the operator until after the fault has been cleared. 5

In order that the nature of the invention may be better understood, reference should be made to the accompanying drawings, Figure 1 of which is a subscriber's line circuit at an unattended 10 automatic exchange, and Figures 2 and 3 show apparatus for conveyance to an attended exchange of the number of a faulty line. One circuit of the type shown in Figure 1 is provided for each subscriber connected to the automatic exchange, one circuit according to Figure 2 is provided for each 50 such subscribers, and the circuit of Figure 3 is provided one for each unattended exchange. As shown, a maximum of 200 subscribers can be accommodated, but this number 15 may be exceeded by obvious circuit additions and modifications.

Reverting to Figure 1, the operation of this circuit is of known character. When the subscriber lifts his receiver, a loop is formed from 25 earth on contact *b*1, over the subscriber's line wires, returning to battery via contacts *b*2, *c*1, and the coil of relay A, which operates. Contact *a*1 removes marking potential derived from contact *b*3 from the contact banks of the local 30 line finders, and contact *a*2 applies earth to a start lead ST which initiates the hunting operation of one or more line finders to find the calling line. 35

When a line finder arrives, an earth potential 40 is extended by it over lead P from the finder circuit to operate relay B, and contact *b*3 locks relay B operated to earth on lead P. Contact *b*4 operates relay C, contact *c*2 of which extends the earth potential from lead P in the line finder 45 circuit to a corresponding lead in the final selector multiple, thus marking engaged the calling subscriber's line therein.

If the subscriber completes the call correctly, 50 subsequent release of the connection results in release of relays B and C, but if for example, impulsion is not completed, a time delay circuit (not shown) connected to the line finder circuit comes into operation. After a predetermined period, earth is removed from the line finder lead P, allowing relay B to release but holding relay C over the loop. At the same time, an earth is applied, from the line finder circuit over lead 55 to operate the "start" relay ST in Figure 2 having access to the caller's line. Relay ST operates

and at contact *st1* (not shown) disconnects the corresponding ST relay serving the other 50 subscribers' lines in the hundred group in which the calling subscriber is connected. This contact is 5 connected in the second circuit in the position shown by the *st1* contact in the dotted rectangle in Figure 2 this contact belonging to the complementary ST relay. Contacts *h3* and *st3* in the other dotted rectangle also belong to the second 10 circuit. Contact *st2* connects relays G and H in series whereupon relay H does not operate, but relay G does. Contact *st3* removes the earth connection from the time delay circuit, thus preventing any other line finder circuit from extending 15 earth over lead 20. Contact *g1* energizes the switch magnet LF which opens the interrupter contacts *lf*. Relay G releases, deenergizing the magnet LF, which releases, moving all its wipers one step forward.

20 This cycle continues, the relay and magnet interrupting one another's circuits until wiper LF4 encounters earth applied to lead 5 via contacts *b5* and *c3* from the line finder circuit over lead M. This potential short-circuits relay G preventing its operation, and operates relay H via contacts *st2* and *h1*. Relay H at contact *h1* locks relay H operated via *g3*, bank LF3, lead 4, *c2*, to earth at contact *b3*, at contact *h2* operates relays HA and R in series via contact *ral*, 25 provided that no other HA relays are operated at that time in series with R, at contact *h3* prevents restoration of earth to the delay circuit on release of relay ST, and at contact *h4* applies earth potential to the line finder circuit over lead 21, thereby freeing the line finder circuit for use by other subscribers and permitting the release of relay ST. Relay HA at contact *ha1* short-circuits the high resistance coil of relay HA (which remains operated) this reduction in 30 resistance preventing the operation of any further HA relay in series with relay R, at contacts *ha2* and *ha3* applies marking potentials to the wipers LF5 and LF6 of the switch LF, at contact *ha4* prepares to operate relay XA, at contact *ha5* 35 prepares an alternative locking path for relay H, at contact *ha6* applies a marking potential to bank DS2, at contact *ha7* reoperates relay G from earth on contact *h5*, and at contacts *ha8* and *ha9* prepares a path for connecting the operator 40 at the attended exchange to the faulty line.

A delay period is now initiated before the operator is informed that a fault has occurred. This delay period is controlled by means of earth pulses applied for example at 1 minute intervals 45 to the lead connected to contact *ha4*. The first of these pulses operates relay XA, and when the pulse is removed, relay XB operates in series over the path:—battery, coil of XA, coil of XB, contacts *xa1* and *r2* to earth. At the end of 50 the next period of 1 minute, a further earth pulse applied via *ha4* holds relay XB operated via contact *xb1*, and short circuits relay XA via contact *xb2*. This relay releases, as also does relay XB at the end of the pulse.

55 Previous to this, however, contact *xb3* operates relay XC which locks operated via contact *xc4* to *r2*. When earth potential is applied for a third time to the *ha4* lead, this potential is now 60 conducted via *xb1* and *xc1* to lead 15 and thence to repeating apparatus of known form which signals the operator at the attended exchange, over a pair of line wires, that a fault has occurred.

Contact *xc3* operates a buzzer relay BZ having 65 a self-interrupting contact *bz1*, this relay, by vi-

brating its contact, supplying a characteristic tone to the operator via *sz1* and lead 14.

When the operator replies to the fault signal as by plugging a cord circuit into the end of the line over which the signal has been passed, relay 5 A is operated over lead 17 by the signalling apparatus at the unattended exchange. This apparatus is of the form of an impulse repeating device, with holding facilities. Relay A at contact *a1* operates relay B which thereupon at contact *b1* removes an earth potential from various points in bank DS1, at contact *b2* removes earth potential from the remaining contacts of this bank, at contact *b3* supplies an alternative locking path for relay R, and at contact *b4* operates 15 relay RA.

The operator now proceeds to transmit a train of single impulses as for example by dialling a succession of 1's by means of a dial or other impulse sending device, counting as she does so. 20 At the commencement of the first impulse, relay A releases, its contact *a1* energizing relay C and the switch magnet DS in series. Relay B is not released, as it is slugged. At the end of the impulse relay A re-operates, and the switch magnet DS moves the wipers DS 1-4 one step forward, though relay C does not release until shortly afterwards. This relay C acts as a guard, its contacts *c1* and *c2* preventing premature operation of certain circuit members at the end of 30 each impulse.

The switch DS is stepped once each time the operator dials an impulse until wiper DS2 reaches the point in its bank marked by contact *ha6*. If the faulty subscriber's line is in the first hundred group, this contact is the second in the bank as shown, if the line is in the second hundred group, then the marking is extended over lead 11 from another HA relay allocated to this second group to the third contact in the bank. 40

When the marking is reached by wiper DS2, relay SZ operates and at contact *sz1* removes tone from the lead 14 connected to the remote operator, thus indicating from the number of impulses dialled, the first digit of the faulty line, 45 at contact *sz3* connects earth potential to certain of the connected contacts of bank DS1, thus stepping the switch DS by self-interruption at its own contacts *ds* to contact 4, and at contact *sz4* holds relay SZ operated to contact *b1*. 50

To regain the tone in order to ascertain the second number of the faulty line, the operator dials a further single impulse. Relay A releases and re-operates as previously described, operating and releasing relay C and stepping the switch DS one step further.

If the next digit of the faulty line is anything other than 1, no marking is found by wiper DS2 and relay SZ releases when C operates, its contact *sz1* re-applying tone to lead 14. This is 60 heard by the operator, who continues to transmit single impulses until a further marking in bank DS2 is encountered to operate relay SZ a second time. This second marking in bank DS2 is derived from the contacts and wiper of bank LF5, 65 the contacts of which bank are commoned or connected together in groups of 10. The switch LF, it will be appreciated, is a 50 point switch and deals with the first 50 subscribers in a hundreds group; a similar switch connected to the leads 70 18 has access to the last 50 subscribers in the group. As each group of 100 subscribers is served by two switches such as LF, the connection to banks LF5 and LF6 are multiplied suitably to the other switches, so that indications may be 75

sent to the operator from any of the switches LF.

The second operation of relay SZ, in removing tone from lead 14 informs the operator of the number of the second digit of the faulty line. If 5 this digit had been 1, then SZ would have remained operated and the tone would not have been re-applied to lead 14, the operator's instructions being such that this would indicate a second digit of 1.

- 10 When the second digit has been transmitted, the operator continues impulsing, relay SZ being released as before, until wiper DS2 encounters the marking made in the associated bank by wiper LF6. The bank associated with this wiper 15 has its contacts connected in groups of ten, thus furnishing an indication of the third and last digit of the faulty line. At the end of the third digit, operation of relay SZ followed by release of relay C connects earth from c1 via s23 to the 20 larger group of connected contacts of bank DS1, the switch DS stepping its wipers by self-interruption to the first contacts in their banks. Relay SZ remains operated via its contacts s24 to contact b1, so that the operator can now connect a speaking or testing circuit to leads 13 and 14 and thence via s21, s22, DS4, DS3, ha9, ha8, LF2 and LF1 to the faulty line, for the purpose of speaking or testing this line. When 25 these operations are completed and the plug withdrawn by the operator, relay A releases followed by relays E, R, RA and XC. The latter relay at its contact xc3 discontinues the operation of the buzzer relay BZ and relay HA is released when contact b3 opens its circuit. Relay HA in turn 30 releases relays H and G, and the apparatus is ready for further transmission.

Should the fault on the line circuit be removed whilst the operator is connected to leads 13 and 14, release of relay C (Figure 1) cuts the 35 circuit of relay H at contact c2, and this relay and relays HA and R all release. The equipment is then restored to normal as though the operator's plug had been removed. If a number of lines become faulty simultaneously, only one fault 40 can be signalled to the operator at any one time, as only one line finder such as LF can be set into operation at any one time. Again, no fault can be signalled twice to the operator, nor seize a line finder circuit, since if the number of a 45 faulty line has been signalled the faulty line is left with its C relay energized in series over the line wires via contacts c1, b2 and b1. This condition, however, is unable to apply a marking to lead 5 since the line finder circuit from which 50 earth potential is derived over lead M has been previously stepped off the faulty circuit when the switch LF reached the faulty line. The line 55 finder cannot again find the faulty line until after the fault has been removed, as relay A cannot be re-operated and consequently contacts a1 and a2 cannot affect the line finder.

We claim:

1. In a telephone system, an unattended exchange, a trunk line extending from said exchange to an attended exchange, means in the unattended exchange responsive to a fault on a line in that exchange for transmitting a signal over said trunk line to an operator in the attended exchange, and means controlled over said 65 trunk line by the operator for enabling such operator to ascertain the number of the faulty line.
2. In a telephone system, a first exchange, a

trunk line extending from said exchange to an operator's board in a second exchange, means for signalling the operator over said trunk line responsive to a fault on a line in the first exchange, and means for enabling the operator to 5 ascertain the number of the faulty line, said last means including an arrangement effective while the operator sends trains of impulses over said trunk line for notifying her when the total of impulses in each train corresponds to a digit 10 of the number.

3. In a telephone system, a first exchange, a trunk line extending from said exchange to an operator's board at a distant exchange, means controlled from a subscriber's line in the first exchange 15 for signalling the operator over said trunk line, switching mechanism at said first exchange controllable by the operator over said trunk line, and means including a device for transmitting signals over said trunk line while 20 said switching mechanism is being operated for enabling the operator to operate it in accordance with the number of said subscriber's line.

4. In a telephone system, a first exchange, a trunk line extending from said first exchange to 25 a second exchange, means in the first exchange responsive to a fault on a line in that exchange for signalling an operator in the second exchange over said trunk line, a step by step switch controlled over said trunk line by the operator to 30 establish connection with the faulty line, and signalling means in the first exchange cooperating with said switch to notify the operator of the number of the faulty line.

5. In a telephone system, a first exchange, a 35 trunk line extending from a switch in the first exchange to an operator's board in a second exchange, a finder in the first exchange responsive to an unstandard condition on a line to find such line, means including said finder for marking the bank of said switch in accordance with the number of the line having the unstandard condition, and signalling means in the first exchange for enabling the operator to control said switch in accordance with said marking, to thereby 40 ascertain the number of the line having the unstandard condition.

6. In a telephone system, a first exchange, a finder in said exchange responsive to an unstandard condition on a line to find such line, a 50 trunk line extending to an operator's board in a distant exchange, means responsive to the operation of said finder for signalling the operator over said trunk line, and a switch controlled by the operator over said trunk line to connect the 55 same with said finder and through the finder to the line having the unstandard condition.

7. In a telephone system, an exchange including a subscriber's line, said line having a lock-out relay, means including said relay responsive 60 to a prolonged calling condition on said line to lock out the line and terminate the calling condition in so far as it affects the switching equipment for extending the line, means responsive to such lock out for signalling an operator in a 65 distant exchange, and means including switching equipment in the first exchange controlled by the operator for advising the operator of the number of the locked out line.
